DESIGN FOR A ROASTER FOR NUTS, COFFEE, OR THE LIKE

Allmand S. White, Norfolk, Va.

Application January 24, 1941, Serial No. 98,373

Term of patent 14 years

To all whom it may concern:

Be it known that I, Allmand S. White, a citizen of the United States, residing at Norfolk, in the county of Norfolk and State of Virginia, have invented a new, original, and ornamental Design for a Roaster for Nuts, Coffee, or the like, of which the following is a specification, reference being had to the accompanying drawing, forming part thereof.

In the drawing:

Fig. 1 is a perspective view of the article, showing my design, looking at the front and one end; and

Fig. 2 is a perspective view looking at the back and opposite end.

I claim:

The ornamental design for a roaster for nuts, coffee, or the like, as shown.

ALLMAND S. WHITE.
